[57] **CLAIM**

The ornamental design for a combined ice and beverage dispenser, as shown and described.

DESCRIPTION

FIG. 1 is a perspective view of a combined ice and beverage dispenser showing our new design;

FIG. 2 is a left-side view thereof shown in FIG. 1 showing the lid/loading chute in the closed position;

FIG. 3 is a top view thereof shown in FIGS. 1 and 2 showing the lid/loading chute in the closed position;

FIG. 4 is a front view thereof shown in FIGS. 1-3 showing the lid/loading chute in the closed position;

FIG. 5 is a bottom view thereof seen in FIGS. 1-4;

FIG. 6 is a left side view thereof similar to FIG. 2 showing the lid/loading chute in the open position;

FIG. 7 is a top view thereof similar to FIG. 3 showing the lid/loading chute in the open position;

FIG. 8 is a front view thereof similar to FIG. 4 showing the lid/loading chute in the open position; and,

FIG. 9 is a back view thereof showing the lid/loading chute in the open position.
